UNITED STATES PATENT OFFICE.

HARRY ALFRED MCKNIGHT AND FRANK ELLIS BURNS, OF SAN FRANCISCO, CALIFORNIA.

ANTISLIP SHOE SOLE.

Application filed February 20, 1924. Serial No. 694,046.

To all whom it may concern:

Be it known that we, HARRY ALFRED MCKNIGHT and FRANK ELLIS BURNS, citizens of the United States, and both residents 5 of San Francisco, county of San Francisco, State of California, have invented a new and useful Antislip Shoe Sole, of which the following is a specification.

This invention relates to wearing soles 10 for shoes and other footwear, of the type provided with means to prevent the user from slipping.

The objects of the invention are to provide soles of the character outlined made of any 15 suitable material or composition, preferably by the vulcanizing method, which will yield an elastic or resilient, cushion like, durable sole and incorporate therein a reinforcing rib and anti-slip structure which 20 will prevent slipping in any direction on wet, icy or other slippery surfaces.

We attain the above desirable objects in the special sole construction shown in the accompanying drawings and in which:

25 Figure 1 is a plan view of our sole as seen from the active surface thereof.

Figure 2 is a cross section along the line 2—2 of Figure 1, and Figure 3 a cross section along the line 3—3.

30 Figure 4 is an enlarged section of the ribs.

To give a clear understanding to the drawings and distinguish from the prior art, it should be stated that our invention 35 lies principally in the manner of ribbing the surface of the sole, of an arrangement of vacuum pockets having an angular relation to the longitudinal axis of the sole, an angular arrangement of ribs within the pockets, 40 and an air or water escape channel for water which would otherwise be forced into the pockets to destroy the vacuum.

In the drawings (1) represents the outer 45 level of the sole taking the form of a relatively wide outer margin connected by angular ribs (1') to an inner rib (1'') forming a loop partly around a central channel (2). This central channel is principally to provide an escape for water or air ordinarily imprisoned between the sole and the pavement.

The channel (2) has a transversely extending portion (3) at the forward end of the sole and terminates rearwardly in a widened discharge channel (4) open to both

side edges of the beveled rear end of the sole. Vacuum pockets (5), (6), (7), (8), (9), (10) and (11) lie between the outer margin and ribs as shown and the angular arrangement relative to the center line of 60 the sole insures the gradual uncovering of, or placing of the pockets in position against the pavement during the act of walking.

It should also be observed that the angle of the pockets (5), (6), and (7) is reversed 65 as against that of (8), (9) and (10). This provides reverse angularly disposed ribs (1') and the forward pocket (11) terminates against a pair of such ribs having lesser angularity, in fact forming almost a right angle 70 crossing with the center line.

Within the vacuum pockets are small V shaped ribs (12) with their apexes terminating on a plane below the level of the outer margin (1) and ribs (1'), (1''). 75 These V ribs (12) it will be observed are placed at an angle to the ribs (1') and are reversed on opposite sides of the center line A so that they extend at a reversed angle from the center line to the angle of the ribs. 80

Particular attention is drawn to the fact that the bases of all ribs (1'), (1'') and (12) are curved. This is important as all these ribs being narrow the constant flexure in use would otherwise speedily crack them 85 off, but at the base of the wide marginal rib it is not so important, due to the much wider connection of this marginal rib to the body of the sole.

In Figure 4 the base curves (13) of the 90 smallest and intermediate ribs are shown in an enlarged representation.

The ribs (12) being below the surface of the surrounding rib surface do not form 95 separate vacuum chambers as they do not touch the pavement at their junctures with the larger ribs, but on account of the yielding nature of the sole they do contact the pavement in the central area of the pockets and assist to prevent slipping and cooperate 100 with the edges of the larger ribs.

By reason of the various angles of the larger ribs elongated corner edges are presented at right angles to almost any slipping movement which the foot wearing such 105 a sole might make, which combining with the vacuum pull of the pockets and the small ribs effectually prevents slipping in any direction.

The water or air channel (2) cooperates 110

2
to prevent slipping by draining the sole so that the spaces can function properly. This drainage channel is closed at the forward end and discharges at the rear and rear sides

5. only, thus avoiding forward or sidewise ejection of the water or mud with its attending nuisance, as with our arrangement the force of the ejection is broken by the heel before being ejected laterally.
10. The broad marginal rib (1) has a multiple function, it takes the heavy wear, forms a protective tie for the small anti-slip ribs within it and also provides the necessary trimming material to make the sole 15 practicable in meeting the exact shape and size of a shoe within reasonable limits.

The aforesaid central channel 2, in addition to the details of construction hereinbefore referred to, is, in fact, bounded by 20 parallel sides or the inner ribs 1'', and what we call a connecting web B, the latter forming an integral part of the material of which the sole is formed. In consequence thereof, any air or water that finds ingress 25 to the channel is held in a very effective manner against lateral displacement. We find that by closing the front end of the channel and opening the rear end thereof and by constituting a principal boundary 30 for the channel consisting of the parallel ribs 1'', and the connecting web A, the entire channel acts in practice very much in the manner of a pump. When the sole is worn it naturally follows that the central 35 part thereof is the first to contact with the surface against which it is brought, and as the front end of the channel 2 is closed and its rear end open, the so-called pump action automatically takes place and as the sole 40 follows its position toward a horizontal against the surface upon which it is brought the channel becomes gradually closed on all sides except for its rear end, where there is free escape of any air or water that is 45 trapped therein. It now follows that having displaced the water, the anti-slip features of the sole both at the front and at the sides thereof are permitted to satisfactorily function, the water or air having cleared 50 itself from these parts to enable these anti-slip surfaces to take effective purchase against the pavement or ground, as obviously follows. In addition thereto the satisfactory displacement of water or air through 55 the alleged functioning of the channel 2 enables the pockets 5, 6, 7, 8, 9, 10 and 11 to freely function as air cushions giving the

maximum measure of buoyancy to the sole, which otherwise could not be had unless for free displacement centrally of the air and 60 water by way of said channel 2.

Having thus described our anti-slip sole it will be seen to possess features especially applicable for use with shoes and the like though its distinctive qualities may make it 65 valuable in other service wherein it is important that one surface shall not slip on another, and any modifications falling within the spirit of the invention which might adapt it to any such other use are 70 intended to be covered in the appended claims.

We claim:

1. A sole formed of elastic material and including a longitudinal channel closed at 75 its front end, open at its rear and provided with parallel sides and a connecting web, the latter forming an integral part of the sole.

2. A sole formed of elastic material and provided at its front portion and along two sides respectively with recesses, each of said recesses having spaced apart ribs, the sole having a longitudinal channel closed at one 80 end and open at its opposite end and connected to the body of the sole by a web forming an integral part of said sole, the said channel functioning through its closed front end and its open opposite end to permit of the effective displacement of air or 85 water from points about the aforesaid recesses so as to permit the ribs of the recesses to satisfactorily function when the sole is brought in contact with a surface.

3. A sole formed of elastic material provided on its wearing surface with toe recesses and a plurality of side recesses, the said plurality of side recesses being separated from each other by a longitudinal channel closed at its front by the toe recesses 95 and open at its rear end and closed at its sides by the side recesses, the toe recesses each provided with a series of angularly disposed ribs, the ribs of the respective toe recesses arranged in diverging relation to a point medially of the sole, and the said side recesses each formed with a plurality of angularly disposed ribs extending respectively at opposite angles to the ribs in the said toe recesses, the ribs in all of said recesses being 105 normally below the plane of the wearing surface of the sole.

HARRY ALFRED McKNIGHT.
FRANK ELLIS BURNS.
